(57) **CLAIM**

The ornamental design for a front end portion of an automobile, as shown and described.

DESCRIPTION

FIG. 1 is a top, front and right side perspective view of a front end portion of an automobile showing our new design; FIG. 2 is a perspective view of right, rear, and top thereof; FIG. 3 is a front view thereof; FIG. 4 is a left side view thereof; FIG. 5 is a right side view thereof; and, FIG. 6 is a top view thereof.

The portions of the automobile shown throughout the drawing views in a deemphasized and faded out half tone form are for environmental and illustrative purposes and form no part of the claimed design.
